WHEEL TRUING DEVICE

Raymond A. Mahlmeister, Dayton, Ohio, assignor
to The Sheffield Corporation, Dayton, Ohio, a
corporation of Ohio

Application March 15, 1944, Serial No. 526,641

5 Claims. (Cl. 125—11)

This invention relates to truing devices for grinding wheels.

One object of the invention is the provision of a grinding wheel truing device of simple and compact construction and capable of operation over long periods of time with an accurate and exact control of the diamond holders by means of which the grinding wheels are trued at desired angles.

Another object is the provision of a truing device embodying a pair of diamond truing bars, slidably mounted in offset planes for movement at an angle to one another and operated by the same slidable part that engages the ends of both bars to positively advance them in the general direction of the grinding wheel.

Another object is the provision of a truing device of the character mentioned, in which the diamond carrying bars are slidably arranged in a pair of guide members that are pivotally adjustable on a common axis on the support on which the bars are arranged.

Another object is the provision of a truing device of the character mentioned, and having a third bar which is rotatable about its own axis to provide circular movement of its diamond to true a cylindrical surface on the grinding wheel.

Other objects and advantages of the invention will be apparent from the following description, the appended claims and the accompanying drawings, in which,

Fig. 1 is a side elevation of a grinding wheel truing device embodying the present invention;

Fig. 2 is a front elevation of the truing device;

Fig. 3 is a bottom plan view;

Fig. 4 is a horizontal section on the line 4—4 of Fig. 1, and,

Fig. 5 is a perspective view of one of the bar guide members and a cooperating spacer block.

Fig. 6 is a vertical section on the line 6—6 of Fig. 2, immediately to the right of the cam 71.

Referring more particularly to the drawings, in which the same reference numerals have been applied to like parts in the several views, 10 designates a carrying bracket adapted to be mounted on the frame structure of a grinding machine which incorporates a grinding wheel 11 adapted to cut a V shaped groove or a screw thread on a workpiece. The carrying bracket 10 may be arranged so that the truing diamonds, and the support 12 which contains the operating mechanism for the diamonds, is located vertically above the grinding wheel axis.

The support 12 is slidably movable on the car-

rying bracket 10 so that the entire support 12 can be moved to a truing position or raised to a withdrawn position above the grinding wheel as shown in Fig. 1. The bracket 10 is thus provided with guideways 14 in sliding engagement with the face of the support. Fixed on the support is a threaded screw 15 the lower end of which extends through guiding lugs 16 on the bracket and is threaded in an adjusting nut 17. Fixed 10 on the nut 17 is a worm gear 18 operated by a worm 19 which is fixed to shaft 20 carrying a hand wheel 21. By turning this hand wheel the nut 17 is rotated to move the threaded screw 15 together with the support 12 to a desired position.

The support 12 rotatably carries a control member 23. In the embodiment of the invention disclosed this control member is rotated through one revolution or through a desired number of revolutions by manual operation, and control member 23 is thus shown as a hand wheel which causes advancing and retracting movements of a pair of truing diamonds 24 and 25 arranged for movement in offset planes and at an angle to one another and to the grinding wheel axis to true the inclined side surfaces 26 and 27 on the grinding wheel. Any suitable contour of substantially V shape can be given to the grinding wheel, but in the particular form of the invention disclosed, the grinding wheel is adapted for cutting screw threads, preferably of the acme type.

Support 12 has spaced parallel walls 29 and 30 and between these walls is a pair of guide members shown as guide blocks 31 and 32 having flat 35 surfaces abutting against the respective side walls. Arranged between the two guide blocks are two spacing blocks 33 and 34. Screws 35 secure each guide block to the adjacent spacing block, and the distance between the walls 29 and 30 is such as 40 to just about receive the blocks 31 to 34 inclusive. With the bottom cover plate 36 removed, these four blocks may be moved upwardly into position and pivot studs 37 and 38 are then inserted into the holes 39 in the support walls and 45 holes 40 in the guide blocks so that the two guide blocks are thus mounted for individual pivotal adjustment about a common axis lying in the plane of symmetry of the grinding wheel. Screws 41 hold the pivot studs in position. Set screws 50 43 and 44 threaded in the support engage against step portions 45 and 46 on the respective blocks 31 and 32 to provide for convenient adjustment from the exterior of the support, of the angular position of the two guide members. Springs 48 55 engaging the cover plate 36 and arranged in sock-

ets 49 in the two guide members serve to hold the step portions of the guide members against the set screws. The guide block 31, spacing block 33 and the side wall 29 of the support 12 are provided with arcuate slots 50 concentric with the pivot studs 37 and 38 and receiving a pair of clamp screws 51 the heads of which press against the outer side of the wall 29. These screws are threaded into the spacing plate 34 which has threaded openings 52 to receive them. Since the spacing plate 34 is secured by the screws 35 to the guide block 32, when the screws 51 are tightened all of these parts are held firmly to one another in the positions to which they are adjusted.

The guide block 31 is provided with an inclined groove 54 which slidably receives the diamond carrying bar 55, which is preferably of rectangular cross section. The end of this bar carries a boss 56 in which the diamond 24 is removably supported in fixed position thereon. The spacing block 33 retains the bar 55 with a sliding fit on the side of the bar. At the upper end of the bar 55 is an offset head 57 having a cam slot 58 which receives a camming pin 59 on cam plate 60, the latter being slidably supported for movement towards and from the grinding wheel axis, as will be presently described. The head 57 on the upper end of the bar 55 carries a pin 61, and surrounding the pin is a compression spring 62 bearing against the head 57 at its upper end, with the lower end of the spring arranged in a hole 63 in the guide block 31. This hole 63 and the pin 61 extend parallel to the longitudinal axis of the bar 55, as will be apparent from Figs. 1 and 5. In a similar manner, the guide block 32 and its cooperating spacing block 34 slidably support the second bar 65 having the diamond 25, although the angle of inclination of the groove in which this bar is arranged is inclined in the opposite direction, or downwardly and to the left as viewed in Fig. 1. The slot 66 in the head of this bar is engaged by the camming pin 67 which is also provided in fixed position on the camming plate 60. As will now be apparent, when the camming plate moves downwardly from a position shown in Fig. 1, the pins 59 and 67 will force the two head portions of the two bars downwardly, the camming pins operating in the slots 58 and 66, and causing exactly the same movement of the two bars generally in a direction towards the grinding wheel. The angles in which the truing points move may be exactly the same with respect to the grinding wheel axis, but at opposite sides of the plane of symmetry of the grinding wheel, or one of these angles may be greater than the other according to the position in which the guide blocks are fixed on the support. Thus a greater inclination can be given to one or the other of the two inclined grinding wheel surfaces when that is required in a truing operation.

The cam plate 60, see Figs. 1 and 2, is provided with horizontally extending pressure faces 69 and 70 engaged by a rotatable cam 71 which is fixed on shaft 72 having the control means or hand wheel 23. As the hand wheel is rotated through one revolution, the cam 71 causes the plate 60 to travel downwardly and then back again, thus advancing and then retracting the truing diamonds. Before the hand wheel 23 is rotated, the other hand wheel 21 is adjusted to bring the diamonds down to a predetermined position so that a cut of the desired depth will be taken on the grinding wheel.

For truing a grinding wheel that is adapted to cut standard V shaped threads, the two diamonds as previously described are all that are required. Where the device is for use with grinding wheels that cut threads of the acme type, a third bar is provided in the support so that it can rotate about its own axis to give a circular movement of its diamond and thus true a cylindrical surface, shown at 74 in Fig. 1. 73 indicates the diamond that accomplishes this. It is carried at the end of a rotatable bar 75, guided at its lower end in a bearing 76 and at its upper end in a bearing sleeve 77 which is held by a screw 78 on the support 12. This bar extends through a wide slot or passage 84 provided in the spacing blocks 33 and 34. A compression spring 79 is seated at its lower end on an in-turned boss or flange on the sleeve 77 the upper end of the spring engaging the overhanging portions of a plate 80 which is fixed to the upper end of the bar 75. This spring thus holds the bar yielding in its retracted position against an adjustable cup 81. The position of the cup 81 is controlled by a threaded stud 82 operated by hand knob 83 to vary the location of the geometric plane containing the circular orbit in which the diamond 73 operates.

Fixed against rotation on the bar 75 is an operating pinion 85. The hub portion of this pinion is provided with a slot 86 engaged by a pin 87 on bar 75 so that the bar can move longitudinally without requiring corresponding longitudinal movement of the pinion. This pinion is in mesh with an operating gear 88 fixed on control shaft 72 so that as the control shaft 72 is turned and operates the cam 71 to oscillate the cam plate 60, it also rotates the bar 75 and thus causes the diamond 75 to turn in a circular orbit and face the cylindrical surface on the grinding wheel. One revolution of the hand wheel 23 is arranged to produce a complete revolution of bar 75 thus causing a complete circular movement of the diamond 73.

The orbit of the diamond 73 is contained in a plane parallel to the axis of the grinding wheel, and the axis of the bar 75 extends perpendicular to the axis of the grinding wheel so that these axes intersect. The extent to which the diamond 73 is offset from the axis of the bar 75 is such that the diameter of its orbit is substantially larger than the width of the cylindrical surface to be trued on the grinding wheel. Thus the diamond passes first in one direction and then in the other direction across the grinding wheel surface as the bar 75 rotates through a complete revolution, the action of the diamond taking place, of course, somewhat above and somewhat below the diametrical plane through the grinding wheel containing the axis of both the grinding wheel and the bar 75.

While the form of apparatus herein described constitutes a preferred embodiment of the invention, it is to be understood that the invention is not limited to this precise form of apparatus, and that changes may be made therein without departing from the scope of the invention which is defined in the appended claims.

What is claimed is:

1. A truing device for grinding wheels, adapted for predetermined positioning on a grinding wheel supporting means, said truing device comprising a support, a pair of guide members pivotally adjustable on said support for movement about a common axis lying in the plane of the grinding wheel, a pair of bars each slidably mounted for

longitudinal movement in a guide member and each having a truing point, said bars being movable at an angle to one another and to the grinding wheel axis, means for adjustably locating each of said guide members on said support to locate the direction of movement of said bars in accordance with the angle desired on the grinding wheel, a common cam plate for simultaneously moving said bars longitudinally in the same general direction to true the wheel, a third bar rotatably mounted in said support for movement about a longitudinal axis extending perpendicularly to the grinding wheel axis, said bar having a truing point for truing a cylindrical surface on the wheel, a rotatable control member, means for rotating said third bar from the control member, and means operated by said control member for oscillating said cam plate.

2. A truing device for grinding wheels, adapted for predetermined positioning on a grinding wheel supporting means, said truing device comprising a support having parallel spaced walls, a pair of guide blocks arranged between said walls and pivotally adjustable on said support for movement about a common axis lying in the plane of the grinding wheel, spacing means between said guide blocks, a pair of bars each slidably mounted for longitudinal movement in a guide member and each having a truing point, said bars being movable at an angle to one another and to the grinding wheel axis, an arm rigid with each of said guide blocks and arranged adjacent one another, and a pair of adjusting screws threaded in said support and respectively engaging said arms for adjustably locating each of said guide blocks on said support to locate the direction of movement of said bars in accordance with the angle desired on the grinding wheel, a cam plate guided in said support and engaging the ends of both of said bars and a rotatable cam for moving said cam plate to simultaneously and equally move said bars in the same general direction to true the wheel.

3. A truing device for grinding wheels, adapted for predetermined positioning on a grinding wheel supporting means, said truing device comprising a support having parallel spaced walls, a pair of guide blocks arranged between said walls and pivotally adjustable on said support for movement about a common axis lying in the plane of the grinding wheel, spacing means between said guide blocks, a pair of bars each slidably mounted for longitudinal movement in a guide member and each having a truing point, said bars being movable at an angle to one another and to the grinding wheel axis, means for adjustably locating each of said guide members on said support to locate the direction of movement of said bars in accordance with the angle desired, a third bar rotatably mounted in said support for movement about a

longitudinal axis extending perpendicularly to the grinding wheel axis, said bar having a truing point for truing a cylindrical surface on the wheel, said spacing means having a passage through which said third bar extends, and means for simultaneously rotating said third bar and reciprocating said other two bars to true the wheel.

4. A device adapted for predetermined positioning on a grinding wheel support, for truing adjacent inclined faces and a short cylindrical face on a grinding wheel, said device comprising supporting means, a pair of bar members, said supporting means having passages in offset planes in which said bar members are longitudinally operable at an angle to one another and to the grinding wheel axis, each of said bar members having a wheel truing point adjacent one end thereof, a common means for operating both of said bar members longitudinally in the same general direction for simultaneously truing inclined faces on the grinding wheel, a bar rotatably mounted in said support for movement about a longitudinal axis extending perpendicularly to the grinding wheel axis, said bar having a truing point arranged eccentric of the bar axis for truing a cylindrical surface on the wheel, said bar having its axis perpendicular to and intersecting the axis of the grinding wheel, and means operated by said common means for rotating said bar through a complete revolution to pass the diamond on said bar across the wheel face in one direction and then the other.

5. A truing device for grinding wheels, adapted for predetermined positioning on a grinding wheel supporting means, said truing device comprising a support, a pair of guide blocks pivotally adjusted on said support for movement about a common axis, means for adjusting said blocks, a pair of bars each slidably mounted for longitudinal movement in a guide block and each having a truing point, said bars being movable at an angle to one another and to the grinding wheel axis, a part reciprocably operable in said support for simultaneously moving both of said bars, a rotatable control member for reciprocating said part, a bar rotatably mounted in said support for movement about a longitudinal axis extending perpendicularly to the grinding wheel axis, said rotatable bar having a truing point arranged eccentric of the bar axis for truing a cylindrical surface on the wheel, said rotatable bar having its axis perpendicular to and intersecting the axis of the grinding wheel, and an operating connection between said rotatable bar and said rotatable control member for rotating said bar through a complete revolution to pass the diamond across the wheel first in one direction and then the other.

RAYMOND A. MAHLMEISTER.
